DESIGN FOR A CANDLE

Carl F. Heeschen, Davenport, Iowa, assignor to
Ruth Clark Neff, Iowa City, Iowa

Application December 26, 1939, Serial No. 89,130

Term of patent 14 years

To all whom it may concern:

Be it known that I, Carl F. Heeschen, a citizen of the United States and a resident of Davenport, in the county of Scott and State of Iowa, have invented a new, original, and ornamental Design for a Candle, of which the following is a specification, reference being had to the accompanying drawing, forming part thereof.

Figure 1 is a front elevational view of a candle showing my design;

Figure 2 is a left side elevational view thereof; Figure 3 is a rear elevational view thereof; and Figure 4 is a right side elevational view thereof.

I claim:

The ornamental design for a candle, substantially as shown.

CARL F. HEESCHEN.
